W. D. STROUD.
Horse Hay-Rake.

No. 223,553.

Patented Jan. 13, 1880.

UNITED STATES PATENT OFFICE.

WILLIAM D. STROUD, OF OSHKOSH, WISCONSIN.

HORSE HAY-RAKE.

SPECIFICATION forming part of Letters Patent No. 223,553, dated January 13, 1880.

Application filed November 14, 1879.

To all whom it may concern:

Be it known that I, WM. D. STROUD, of Oshkosh, in the county of Winnebago and State of Wisconsin, have invented certain new and useful Improvements in Horse-Rakes; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to horse-rakes; and it consists in the improvements in the construction of the same hereinafter fully described, and particularly pointed out in the claim.

In the drawings, Figure 1 represents a top view of my improved rake; Fig. 2, a section on the line *x x* of Fig. 1; Fig. 3, a section on the line *y y* of Fig. 1; Fig. 4, a detached sectional view, showing the clutch and mechanism for throwing the rake-shaft into gear with the wheel; Fig. 5, a detached view of one of the rake-sections, and Fig. 6 a detached front elevation of the ratchet-wheel and the pawl for operating the same.

The letter A indicates the truck or frame of the rake, which is provided with a series of bearings, B, in which is journaled a shaft or axle, C, which is capable of turning freely in said bearings. The said bearings are arranged at equal distances apart, and between them are located the rake-sections D, consisting each of two sets of rake-teeth, which are passed through the short beams E, which are parallel with the shaft or axle C, and arranged on opposite sides of the same. The ends of the opposite sets of teeth, after passing through the beams, are curved in opposite directions around the shaft, so as to confine the sections securely thereon.

Midway between the ends of the shaft or axle C, and secured to the same, is a disk, F, the periphery of which is divided into quarters, two opposite quarters being provided with ratchet-teeth *f*, and the other opposite quarters, *g*, being left plain.

The letter G indicates a spring-pawl con-

nected by a rod, H, to a lever, I, fulcrumed to the front of the frame A in such position as to be readily under control of the driver. Said lever is connected, by means of link K, to an angle-lever, L, fulcrumed to the frame, and said lever K connects with a lever, M, which is bifurcated at its lower end, and sets over the shaft or axle C, just behind a spring-clutch, N, secured to said shaft. Said clutch consists of a loose sleeve provided with projections *n*, extending through recesses in a rigidly secured shoulder on the axle or shaft. Said sleeve contains a spiral spring, O, which keeps the sleeve in a normal position—that is, thrown back so as to release the projections *n* from the apertures P.

The letter P indicates a series of apertures in the face of the wheel, with which the projections on the sleeve may be caused to engage, when the sleeve is shifted from its normal position, through the medium of the various levers.

The rake, when one set of its teeth is in working position, is held by the spring-pawl G, which enters one of the ratchet-teeth *f*; but when it is desired to shift the rake for dumping, by operating the lever I the spring-pawls G and N will be operated, one to release the ratchet-teeth *f* and the other to engage the apertures P in the wheel, thereby throwing the parts into such position as to cause the wheel to rotate the axle a half-revolution, and carry the rake-teeth of one set between the clearing-teeth R, secured to the rear of the frame, the other set being thrown into working position.

The face of the disk F is provided with a series of radial ratchets, with which one end of a lever, S, fulcrumed to the axle, is adapted to engage, the forward end of said lever being under the control of the driver. This lever is for the purpose of enabling the driver to adjust the rake-teeth irrespective of the operation of the wheel when it is necessary, which is done by elevating the forward end of the lever, then causing its rear end to engage the proper ratchet-tooth on the face of the disk F, and then depressing the forward end of said lever so as to rotate the disk.

Having thus described my invention, what I claim, and desire to secure by Letters Patent, is—

In combination with the axle of a horse-rake, the parallel beams on opposite sides of the same, and the rake-teeth passing through said beams and bent around the axle, substantially as and for the purpose specified.

In testimony that I claim the foregoing I have hereunto set my hand this 6th day of November, 1879.

WM. D. STROUD.
